JOSEPH ZYGMAN

BY *J. Zygman*
ATTORNEY.

UNITED STATES PATENT OFFICE.

JOSEPH ZYGMAN, OF GREENWICH, CONNECTICUT.

RAIL-JOINT.

1,385,197.

Specification of Letters Patent. Patented July 19, 1921.

Application filed May 21, 1921. Serial No. 471,491.

To all whom it may concern:

Be it known that I, JOSEPH ZYGMAN, citizen of Poland, residing at Greenwich, in the county of Fairfield and State of Connecticut, have invented certain new and useful Improvements in Rail-Joints, of which the following is a specification.

This invention relates to rail joints and it has for an object to provide a simple arrangement of parts whereby the ends of the rails may be securely fastened together in a manner to prevent the fastening means from becoming loosened accidentally.

For further comprehension of the invention, and of the objects and advantages thereof, reference will be had to the following description and accompanying drawings, and to the appended claims in which the various novel features of the invention are 20 more particularly set forth.

Figure 1 of the drawings is a plan view showing a pair of separated rail ends constructed according to the invention.

Fig. 2 is a side view thereof.

Fig. 3 is a transverse vertical section with the rail ends joined, this view being taken at the point indicated by the line 3—3 in Fig. 2.

Fig. 4 is an end view of the locking bolt.

Fig. 5 is a fragmentary longitudinal section of the bolt, showing the releasing key in engagement therewith.

In the drawings the reference numerals 10 and 11 indicate adjacent rail ends, and 12 35 the ties. In constructing my improved rail joint the rail end 11 is formed with a projecting tongue which comprises a base-element 13 forming an extension of the base flange of the rail but flattened on its top surface as well as on its bottom surface. The 40 tongue also comprises a somewhat thickened extension 14 of the web which is of about one-half the height of the web and has lateral lugs or projections 15 on its outer ends.

The rail end 10 is formed with a complementary recess to receive the tongue on the other rail end and to enable this recess to be formed in the rail end 10 the web of the latter is thickened as at 16, the sides of 45 this thickened portion extending downwardly and outwardly from the side edges of the tread to the side edges of the base flange.

The recess in the rail end 10 comprises a 50 check-out 18 on the bottom thereof to receive the base-flange portion 13 of the tongue on

rail 11. From this check-out 18 the thickened rail end 11 is slotted upwardly as at 19 to form a recess adapted to receive the web portion 14, this recess having lateral 60 offsets 20 at its inner end which accommodate the lugs 15.

To hold the assembled rail ends against vertical displacement I provide a pair of longitudinally movable locking bolts 22 65 which are accommodated in sockets or recesses such as 23 in the thickened web element 16 of the rail 10, the tongue on rail 11 having registering recesses such as 24 in the end face thereof into which said bolts are 70 adapted to project, the bolts being normally urged into said recesses by coiled expansion springs such as 25 located in the sockets 23 and bearing against the rear ends of the bolts 22.

To enable the bolts 22 to be completely drawn into the sockets 23 when the rail ends are being assembled or disassembled I form in the rear end of each bolt a recess 26 which is partially covered by a slotted end piece 75 27, this end piece presenting a pair of intersecting slots 28 whereby a T-headed key 29 may be inserted into the recess 26 and, upon being given a partial turn, engage the end piece 27 and so enable the bolt to be 80 withdrawn from the socket 24 by pulling on the key against the spring 25. Suitable slots 30 lead into the recesses 23 from the rear ends of the web members 16 for the 85 insertion of the key 29.

It is believed that the manner of use and operation of my improved rail joint will be readily understood from the above description.

Having thus described my invention what 90 I claim as new and desire to protect by Letters Patent of the United States is as follows:

1. A pair of rail ends having interlocking elements preventing longitudinal displacement, and a bolt carried in a longitudinal socket in one rail end and projecting into a registering longitudinal socket in the other rail end.

2. A pair of rail ends having interlocking elements preventing longitudinal displacement, and a bolt carried in a longitudinal socket in one rail and projecting into a registering longitudinal socket in the other rail end, and a coiled expansion spring inserted 105 in said first socket behind said bolt.

3. A pair of rail ends one of which has

- an extended tongue formed by a base-flange element and a web extension having lateral lugs at its forward end, said base-flange element being flattened on its top side, the 5 other rail end having a thickened web portion and having its base-flange checked-out to receive the base-flange element on the said tongue and having a T-slot extending upwardly from the said checked-out portion.
- 10 4. A pair of rail ends having interlocking elements preventing longitudinal displacement, and a bolt carried in a longitudi-

nal socket in one rail end and projecting into a registering longitudinal socket in the other rail end, and a coiled expansion spring inserted in said first socket behind said bolt, 15 said bolt having a recess in one end, a slotted head covering said recess and adapted to be engaged by a key to withdraw the bolt completely into the first socket. 20

In testimony whereof I have affixed my signature.

JOSEPH ZYGMAN.
